UNITED STATES PATENT OFFICE.

HERBERT FLEETWOOD HOLWORTHY, OF CHURCH STRETTON, ENGLAND.

EXERCISING APPARATUS.

1,104,505.

Specification of Letters Patent. Patented July 21, 1914.

Application filed December 21, 1912. Serial No. 737,980.

To all whom it may concern:

Be it known that I, HERBERT FLEETWOOD HOLWORTHY, a subject of the King of England, residing at Church Stretton, Salop, England, have invented certain new and useful Improvements in Exercising Apparatus, of which the following is a specification.

This invention relates to portable exercising apparatus of the horizontal bar type and is devised so that it may be fitted up in private houses, preferably, though not necessarily, in connection with a door-way, as affording extra room for exercising on the bar.

According to the present invention a portable exerciser is provided comprising a base, standards projecting therefrom, an exercising bar connecting the standards, bracing members extending from the main structure, and anchorages for the bracing members with or without devices for permitting and resiliently-resisting movement of the exercising bar aforesaid. In the preferred construction the exerciser has devices whereby the standards, exercising bar, and bracing members may be readily detached from their connection with adjacent parts, while at the same time the standards and bracing members are constituted by parts mutually adjustable for length and devices for securing the parts in adjusted position. The preferred construction also comprises means carried by a door-frame or the like whereby the bracing members may be anchored in order to become operative against swaying of the exerciser and as distances for positioning the main structure thereof in relation to the said door-frame or the like anchorage.

The accompanying drawings illustrate specific constructions of exerciser according to this invention.

Figure 1 is a perspective view of the device erected adjacent to doorway, and shows certain additional apparatus attached. Fig. 2 is a side view of part of the device shown in Fig. 1. Fig. 3 is a side view of a supplementary platform, with extensions in one position. Fig. 4 is a similar view to Fig. 3 with a small part in section and the extensions in another position. Fig. 5 is a part sectional side view of one of the standards of the main structure in a modified form of the exerciser. Fig. 6 is a modified form of holding device for the exerciser bar and 6^a for the feet of the standards. Fig. 7 illustrates the exerciser bar and telescopic parts of the standards formed as one piece, and

Fig. 8 shows a modified form of complete exerciser in which only one standard is employed.

The apparatus starting from the floor comprises a base A to which are screwed two metal shoes B with sockets B¹ to receive the standards C presently to be described. The shoes B are shaped with long webbed feet B² to withstand any lateral play. The platform lies upon the floor and conveniently is oblong in shape it may be made of polished wood with the middle portion lined with felt and covered with cork linoleum, which being a non-conductor of heat will add to the comfort of the user in cold weather. The standards C are constituted by tubes preferably fitted in the shoe sockets B¹ by a strong bayonet joint C² B², so that when the apparatus is being erected it is merely necessary to drop the lower ends of the standards into the sockets, and slightly rotate the tubes, when they will become locked in position. The shoes themselves may be detachably secured by spring clips borne by the base A, instead of by screwing them in place. At their upper ends, the main tubes C of the standards are split as at C¹ and adapted, as for example by means of the split lugs C³ and clamping bolts C⁴, to grip the telescopic extension tubes C⁵ whose upper ends are formed as rings or sockets C⁶ (see Fig. 2) to receive the horizontal exercising bar D; if preferred, the two telescopic tubes and the horizontal bar may be formed as a single member as in Fig. 7, or they may be independent of each other, the bar merely slipping into spring clips C⁷ on the tops of the extension tubes C⁵ as in Fig. 6.

Anchorages in the form of socket brackets X¹ are in this construction fixed to a door-frame X to receive telescopic bracing rods or tubes E E¹ extending horizontally from lugs E² adjustable in position upon the extension tubes of the main structure, and taper-pins E³—secured by chains E⁴ so that they may not get lost—are used to secure the ends of the strut respectively in slots in the anchorages X¹ on the door-frame and in the socket lug E² borne by the telescopic extension tubes C⁵. These struts are telescoped and clamped by means of splits E⁵ collars E⁶ and bolts E⁷ in the same way as the main tubes so that their length can be properly adjusted. These parts are constructed to withstand the backward and forward thrust on the apparatus while it is being used.

If the exercising bar is made detachable, it is preferred to make the ends D¹ oval as seen in Fig. 2 or otherwise non-circular in shape, so that the bar itself will not turn around in the hands of the operator. It will be understood that all the lugs or their equivalents may be split and bolted so as to lock securely upon their respective tubes. The tubes may be of cold solid-drawn steel, finished in fine cycle enamel, while the lugs and shoes are preferably of malleable iron and may be plated or given an aluminium finish. For certain exercises it is advantageous to employ a supplementary or exercising platform F lying transversely to the exercising bar and to the main platform or base A. This supplementary platform comprises a grooved pedestal which straddles the main platform or base A and positioned thereon by dowels F² and when desirable has hinged extension boards F³ F⁴ fitted with suitable folding supports F⁵, whereby the extension boards may either be held in alignment with the portion lying on the main platform, or slope therefrom down to the floor as will be clear from Figs. 3 and 4.

It will be seen that the apparatus described is almost entirely self-contained and is portable and adjustable to any desired height. It can be set up in almost any room and fitted either in front of a window or a doorway, or of course it may also be used in the open air, and the references hereinbefore to the doorway and door-frame, are only to be interpreted as being examples. The apparatus may be fitted up in any similar convenient position.

If desired the telescopic tubes may contain devices adapted to permit and resiliently resist movement of the exercising bar, as the resulting resistance or spring is of service in some exercises. This is accomplished according to one method by the employment of coiled springs G which abut at one end against plugs G¹ in each of the main tubes and at the other end against plugs G² in the telescopic extension tubes. The collars C³ are then slackened off so as not to grip the tubes in the ordinary way, while the slots C¹ receive stop pins C⁸ for limiting the movement of the bar D. The spring device can if desired be rendered inoperative by tightening up the clamps C³ as for ordinary use. Furthermore, in order to make the ap-

paratus as complete for all exercises as possible, rings H may be suspended from the exercising bar by adjustable slings H¹, while an additional cross-bar K adjustably clamped as at K¹ to the standards C may also be provided.

Fig. 8 indicates a simple modification wherein only one standard C⁹ is used, the long bracket C¹⁰ secured to the door jamb being substituted for the other standard. In this case the main exercising bar D connects door-frame and standard, adjustment for height at the door-frame being arranged for in the bracket C¹⁰ by the series of holes C¹¹ each of which may receive the fastening pins C¹² according to the adjustment desired. To counteract swaying the platform is extended in the direction parallel with the doorway so as to form an L or T and an extra large shoe for the standard is used. The platform proper extends between the standard C⁹ and the door frame, as will be obvious from Fig. 8.

What I claim as my invention and desire to secure by Letters Patent is:—

1. A portable exerciser comprising a base plate, a plurality of standards mounted thereon, a telescopic extension in each of said standards, a resilient mounting for each of said extensions, a horizontal bar connected to said extensions and means for securing said extensions to the standards to render the resilient mountings inoperative; substantially as described.

2. A portable exerciser comprising a base plate, a plurality of standards thereon, a telescopic extension in each of said standards, a resilient mounting for each of said extensions within the standards, frictional means for clamping the extensions to the standards, a horizontal bar connected to the upper ends of said extensions, and a horizontal brace rod extending from each extension, said brace rods being arranged to resist tension and compression stresses; substantially as described.

In testimony whereof I have signed my name to this specification in the presence of two subscribing witnesses.

HERBERT FLEETWOOD HOLWORTHY.
